Figure 5

FIG. 1 is a perspective view of the boat of this invention.

FIG. 2 is a side view thereof, the reverse side being substantially a mirror image thereof.

FIG. 3 is a top view thereof.

FIG. 4 is a front perspective view thereof.

FIG. 5 is a back perspective view thereof.

The characteristic features of our design reside in the sharply pointed bow and the low profile, swept-back opaque wrap-around windscreen as best seen in FIG. 1.

We claim:

The ornamental design for a boat, as shown and described.
